UNITED STATES PATENT OFFICE.

MORRIS L. ORUM, OF PHILADELPHIA, PENNSYLVANIA.

CUTTER-HEAD.

SPECIFICATION forming part of Letters Patent No. 269,815, dated December 19, 1882.

Application filed September 9, 1882. (No model.)

To all whom it may concern:

Be it known that I, MORRIS L. ORUM, of the city and county of Philadelphia, in the State of Pennsylvania, have invented certain new 5 and useful Improvements in Rotary Cutters, of which improvements the following is a specification.

The object of my invention is to provide a cutter adapted to form a recess which, commencing at its bottom, is dovetailed or undercut for the major portion of its depth, and for the remainder is cut out to a width greater than that of the top of the dovetail.

To this end my improvements consist in the 15 combination of a cutter-head, a recessing-cutter secured thereto, and a spur-cutter; also, in the combination of a cutter-head, a dovetail recessing-cutter, a plain recessing-cutter, and a spur-cutter.

20 The improvements claimed are hereinafter more fully set forth.

In the accompanying drawings, Figure 1 is a plan or top view of a rotary cutter embodying my invention; Fig. 2, a side view in elevation of the same, and Fig. 3 a transverse section at the line $x-x$ of Fig. 1.

To carry out my invention I provide a cylindrical cutter-head or carrier, A, which is formed upon or secured to a central stock or 30 spindle, a , suited for connection to a shaft rotated by a proper prime mover. A dovetail recessing-cutter, B, (one or more,) having its edge inclined at an angle corresponding to the desired inclination of the dovetailed or undercut portion of the recess to be formed, is secured to the cutter-head A by a clamp, b , and stud b' , adjustability of the cutter B outwardly 35 to compensate for wear being provided for by fitting a flange or inclined rib, b^2 , on its lower side, in a groove in the cutter-head, which is eccentric to the axis of the cutter-head and spindle. A downwardly-inclined rib, b^3 , which is curved concentrically with the lower flange of the cutter B and the groove in which the 40 latter rests, is formed on the end of the clamp b and fits in a corresponding groove on the cutter above the flange b^2 . The double inclined bearing of the cutter-head and clamp

on the cutter, which is thus provided, enables the cutter to be held firmly in its adjusted position without the risk of displacement outwardly when in operation. A plain recessing-cutter, C, (one or more,) is secured to the cutter-head by a clamp, c , and stud c' , and is adapted to be adjusted outwardly in a similar 50 manner to the dovetail-cutter B—that is to say, by having a lower rib or flange fitting in an eccentric slot in the cutter-head. The clamp c may, if desired, have a downwardly-inclined rib fitting a similar groove in the cutter, so as 55 to hold the cutter C in a similar manner to the dovetail-cutter B.

In order to obviate the splitting of the wood in which the recess is to be made by the dovetail-cutter when working against the grain, I 60 secure to the cutter-head, in advance of the leading edge of each dovetail-cutter, a spur-cutter D—that is to say, a cutter whose edge is perpendicular to the axis of the cutter-head, and which effects a scoring cut at or about the 65 center of the inclined cut made by the dovetail-cutter B. The spur-cutters are by preference fitted in slots in the clamps c of the cutters C, and are retained therein by studs d , which permit of their adjustment as from 70 time to time required to compensate wear.

I claim as my invention and desire to secure by Letters Patent—

1. The combination, substantially as set forth, 75 of a cutter-head, a recessing-cutter, and a scoring spur-cutter secured to the cutter-head in advance of the leading edge of the recessing-cutter, and between the extremities thereof, so as to divide the shaving which is removed by said cutter.

2. The combination, substantially as set forth, 80 of a cutter-head, a dovetail-cutter, a plain recessing-cutter whose edge is perpendicular to the axis of the cutter-head, and which effects a scoring cut between the extremities of the 85 inclined cut made by the dovetail-cutter and a spur-cutter.

MORRIS L. ORUM.
